UNITED STATES PATENT OFFICE.

ANNA K. ASHMON, OF SALEM, OREGON.

CHIMNEY-HOLDER.

1,223,233.

Specification of Letters Patent.

Patented Apr. 17, 1917.

Application filed January 23, 1917. Serial No. 144,089.

To all whom it may concern:

Be it known that I, ANNA K. ASHMON, a citizen of the United States, residing at Salem, in the county of Marion and State of Oregon, have invented new and useful Improvements in Chimney-Holders, of which the following is a specification.

The present invention relates to a chimney holding device for lamp burners.

10 In carrying out my invention it is my purpose to produce an extremely simple, cheap and thoroughly effective device of this character comprising a band adapted to encircle the lower portion of the chimney or that portion engaged by the spring arms of the burner, the said band being provided with spring means whereby the same is removably associated with the said spring arms of the burner and whereby the band 20 and arms will coöperate to draw the arms in the direction of the band and to retain the band in frictional engagement with the chimney.

I accomplish the above objects and others 25 by a construction and combination of parts, a satisfactory exemplification of which being illustrated by the accompanying drawing in which:

Figure 1 is a perspective view illustrating 30 the application of the improvement,

Fig. 2 is a central sectional view taken through the retaining band,

Fig. 3 is a perspective view of the band in 35 its spread condition and looking toward the inner face thereof, and

Fig. 4 is a sectional view approximately on the line 4—4 of Fig. 3.

In the drawing, the numeral 1 designates 40 any ordinary construction of burners provided with the spring chimney engaging arms 3, and the numeral 3 designates the chimney which is arranged upon the burner. Disposed to surround the lower tubular portion of the chimney which is engaged by the 45 spring arms 2 of the burner is a flexible metallic band 4. The band upon its outer face is provided with a plurality of longitudinally arranged spring catch members 5, corresponding in number with that of the 50 arms 2. One end of the band is provided with an eye 6, and the other end forms what may be termed a tongue which is designated by the numeral 7 and which is adapted to be passed through the eye 6 and to be bent

around the said eye. The band 4, at a suitable distance from the eye and from the tongue thereof has its edges inturned over its inner face, as indicated by the numerals 8, and the said bent edges are adapted to engage a strip 9 of compressible non-heat 55 conducting material, such as a strip of asbestos or the like. By this arrangement it will be noted that the band may be firmly clamped around the chimney and that the chimney may be arranged upon the burner 60 and rotated so as to permit of the catch members 5 each engaging with one of the spring arms 2 of the burner, thus forcing the arms toward the chimney and tending to more tightly clamp the band upon the 70 chimney. The device, it will be noted, is extremely simple, and when arranged as above described will positively prevent the accidental removal or dropping of the chimney from the burner.

Having thus described the invention, what I claim is:

1. In combination with a burner having spring arms and a chimney engaged by the arms, of a band surrounding the burner and 80 engaged by the spring arms whereby to frictionally engage between the said arms and the said chimney, and said band having an inner compressible facing.

2. In combination with a burner having 85 spring arms and a chimney engaged by the arms, of a band surrounding the chimney and contacted by the arms, a compressible strip upon the inner face of the band, and spring means upon the outer face of the 90 band engaging with the arms of the burner, as and for the purpose set forth.

3. In combination with a lamp burner having spring arms and a chimney engaged by the arms, of a flexible metallic band disposed to be arranged to surround the chimney and to be contacted by the arms, said band having one of its ends formed with an eye and its other end formed with a bendable tongue adapted to be passed through the eye 100 and to be bent over the said eye, a facing of compressible non-heat conducting material upon the inner face of the band, and means upon the outer face of the band for engaging with the spring arms of the burner. 105

4. In combination with a burner having spring arms and a chimney adapted to be engaged by the arms, of a split band dis-

posed to surround the chimney and to be contacted by the arms, means upon the edges of the bands for adjustably retaining the same upon the chimney, said band having 5 its longitudinal edges inturned, a strip of compressible non-heat conducting material arranged between the said edges, and longi-

tudinally arranged spring catch members upon the outer face of the band adapted to engage one with each of the spring arms 10 of the burner.

In testimony whereof I affix my signature.

ANNA K. ASHMON.
